UNITED STATES PATENT OFFICE

118,495

DESIGN FOR A TABLE RADIO

Richard Dardess, Chatham, N. Y.

Application August 22, 1939, Serial No. 86,829

Term of patent 7 years

To all whom it may concern:

Be it known that I, Richard Dardess, a citizen of the United States of America, residing at Chatham, in the county of Columbia and State of New York, have invented a new, original, and ornamental Design for Table Radio, of which the following is a specification, reference being had to the accompanying drawing, forming part thereof.

In the drawing:

Figure 1 is a top plan view of a table radio, showing my new design; and

Figure 2 is a side elevational view of the same, the opposite side of the table radio is the same as that shown in Fig. 2 with the dial opening omitted.

I claim:

The ornamental design for a table radio, as shown and described.

RICHARD DARDESS.
